CLAIM

The ornamental design for a scanner, as shown and described herein.

DESCRIPTION

FIG. 1 is a front, top, and right side perspective view of a scanner;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof; and,

FIG. 7 is a left elevational view thereof.

Those portions of the Figures shown in broken lines are included for illustrative purposes only and form no part of the claimed design.

1 Claim, 7 Drawing Sheets
